United States Patent Office.

WILLIAM W. HANSCOM, OF SAN FRANCISCO, CALIFORNIA.

Design No. 5,026, dated June 20, 1871.

DESIGN FOR A STEAM-PUMP.

The Schedule referred to in these Letters Patent and making part of the same.

To all whom it may concern:

Be it known that I, WILLIAM W. HANSCOM, of the city and county of San Francisco and State of California, have originated a new Design for a Steam-Pump, of which the following is a full, clear, and exact description, reference being had to the accompanying drawing making part of this specification.

A is a steam-cylinder.

B, a water-cylinder, connected together by the plate C and stays D, which stays carry a box or support for the fly-wheel E.

The fly-wheel being placed in front of the piston

and connecting-rods, and operating the valve by means of the eccentric groove in its face, produces a light, neat, simple, and strong appearance of working and stationary parts.

What I claim as my invention, and desire to secure by Letters Patent, is—

The design for a steam-pump, herein set forth.

W. W. HANSCOM.
